UNITED STATES PATENT OFFICE.

JAMES LIPPINCOTT AND THOMAS BAKEWELL, OF PITTSBURG, PA.

DESIGN FOR A LABEL.

Specification forming part of Design No. 7,303, dated March 31, 1874; application filed March 6, 1874.
 [Term of Patent 7 years.]

To all whom it may concern:

Be it known that we, JAMES LIPPINCOTT and THOMAS BAKEWELL, of Pittsburg, in the county of Allegheny and State of Pennsylvania, have invented a new and useful Design for Label; and we do hereby declare the following to be a full, clear, and exact description thereof, reference being had to the accompanying drawing making a part of this specification, which shows our improved design.

This drawing consists of our firm-name—“Hubbard, Lippincott, Bakewell & Co., Pittsburgh, Pa.” arranged in a figure, and surrounded by any suitable border, and inclosing the word “patent,” followed by the representation of an eye; also the words “and Poll, Old Bullion Axe, Lippincott & Co.”

What we claim herein, and desire to secure by Letters Patent, is—

The design for label, described and shown. In testimony whereof, we, the said JAMES LIPPINCOTT and THOMAS BAKEWELL, have hereunto set our hands.

JAMES LIPPINCOTT.
 THOS. BAKEWELL.
